UNITED STATES PATENT OFFICE.

CLARK FRANCIS FISK, OF ALLENTOWN, NEW JERSEY, ASSIGNOR OF ONE-HALF TO
ROBERT C. DUNHAM, OF TRENTON, NEW JERSEY.

PNEUMATIC TUBE.

1,135,273.

Specification of Letters Patent. Patented Apr. 13, 1915.

Application filed February 6, 1913. Serial No. 746,809.

To all whom it may concern:

Be it known that I, CLARK FRANCIS FISK, a citizen of the United States, residing at Allentown, in the county of Monmouth and State of New Jersey, have invented certain new and useful Improvements in Pneumatic Tubes; and I do declare the following to be a full, clear, and exact description of the invention, such as will enable others skilled in the art to which it appertains to make and use the same.

This invention relates to pneumatic tires, and more especially to the inner tubes thereof; and the object of the same is to produce such a tube having fabric strips along its rim and tread sides, which strips are of such construction and application that in the finished inflated tube their mesh is in normal condition—neither stretched nor contracted.

Other minor objects appear throughout the following specification, with means for carrying them out.

This principal object I propose to accomplish by cutting the canvas or friction duck in strips which go on the outer and inner sides of the tube, applying the former in their normal condition, and expanding the latter before they are applied.

The following specification sets forth the preferred method of making my improved tube, reference being had to the accompanying drawings wherein—

Figure 1 is a plan view of a piece of fabric, showing how the same is cut into the strips. Fig. 2 is a plan view of a portion of one of said strips after it has been expanded. Fig. 3 is a fragmentary detail showing how the transverse center of this strip could be expanded to a slightly greater degree than its edges. Fig. 4 is a plan view of another piece of fabric, indicating how a strip may be cut straight (not bias) and applied to the outer side of the tube without expanding. Fig. 5 is a section through a mandrel, showing the constituent elements of my improved tube in place thereon; and Fig. 6 is a cross section of the tube as built up from these elements and stripped off of the mandrel. Figs. 7 and 8 illustrate slight modifications or amplifications of the idea, in the former of which the edges of the fabric strips are lapped and in the latter of which the edges at one side are lapped and the other

edges are spaced to provide for expansion of the tube as will be explained hereinafter. Fig. 9 is a cross section of a still further modification or amplification, in which the fabric strips are spaced on both sides and the strips of rubber are employed to overlie both expansion bands; and Fig. 10 is a cross section showing that the fabric strips on the outer or tread side of the tube may be duplicated. I have also employed this view to show that the tube might be armored (especially if it is of the hose-pipe variety and is to be used without an outer tube or casing), as by the insertion of metallic plates, leather, or the like. Fig. 11 is a diagrammatic section taken through a finished tube in a plane transverse to its axis, showing how a multiplicity of layers of fabric could be applied so that their ends would come together, but the meeting line in each layer would break joint with that in the next.

The prevailing method for making standard inner tubes for pneumatic tires is to shape them on a mandrel, cut them into lengths, and bring the ends of each length together and connect them; but the objection to this method is that the finished article is made to fit the tire casing on its inner or rim side, and its outer or tread side expands when it is inflated and while under such expansion when in use it is stretched and therefore more likely to become punctured or blown out than otherwise. Substantially the same method is followed when tubes are made which have fabric such as canvas or friction duck applied to one or both faces of or embedded in the material of which the tube is formed, but when the ends of the tube are brought together, connected, and inflated, the outer side cannot expand because of the presence of the fabric and therefore the inner side must wrinkle, and these wrinkles contacting with the rim side of the outer tube or casing cause rapid wear and shorten the life of the tube. After long experiment I have discovered that if the fabric at the outer side of the tube be applied in strip form in its normal condition, while that at the inner side is stretched or "expanded" before it is applied, when the ends of the tube are brought together and connected the fabric in the inner or shorter side will contract automatically as the tube is inflated, with the result that

there will be no wrinkles along the rim side and no undue tension along the tread side, and therefore the finished article will wear much longer.

5 In the accompanying drawings, Fig. 1 shows a sheet of woven fabric, and the lines across the same indicate how I cut a strip from the same on the bias; and Fig. 2 shows the same strip after it has been 10 stretched or forcibly expanded to the extent that its meshes are of different shape than in Fig. 1. Fig. 3 shows a detail I may employ, and this consists in expanding the fabric strip 1 to a little greater degree along 15 its transverse center than at either edge. As the center of this strip is the part that will be nearest the hub and will therefore follow the smallest circle within the tube, and it should be expanded most because it will 20 have to expand most for its mesh to resume its normal condition. However, this is a detail which may well be left to the manufacturer. In Fig. 3 the numeral 2 designates the transverse center of this strip 1, the center 25 being supposed to be expanded more than the edges. The numeral 3 in Fig. 4 designates a strip which is cut straight across the fabric 4, and a strip so cut might be applied to the outer or tread side of the 30 tube. The fabric may be canvas, friction duck, or any material which is commonly employed in this connection. Fig. 5 shows one manner of assembling the constituent elements of this tube around a mandrel M, 35 herein shown as a steel tube of proper circumference to form the bore of the pneumatic tube being made. In forming the pneumatic tube on this mandrel, I cut the rubber into a sheet 5 whose length corresponds 40 with that of the circumference of the finished article and whose width is about twice the circumference of the tube when finished. One edge of this sheet 5 is laid on the mandrel M, preferably at a point 6 as indicated, the sheet is then carried once around the mandrel to the point of starting, a strip of the bias and expanded fabric 1 is then laid beneath the mandrel and a strip of let us say "normal" (i. e. unstretched) fabric 45 50 is laid over the mandrel, and the rubber sheet 5 given a second wrap around the same so that it incloses the two fabric strips between its own two convolutions as shown in Fig. 6, and what was its outer edge 7 at 55 first is here shown as standing about over its inner edge or point of starting 6. The article as thus far constructed is now wrapped and cured, and then stripped from the mandrel when the expanded inner side will contract 60 slightly so that the ends of the tube can be brought together, and they are joined by any of the well known means; and later when the tube is inflated the bias expanded fabric on the rim side will contract freely 65 back to its normal mesh and settle to fit the

tire shoe cavity without wrinkles. It will be noted therefore, that in the finished article the rubber and the fabric are nowhere under undue tension when the tube is inflated. In fact, if the tube could be inflated without its ends being connected, it would be found that it would automatically assume a circular shape if my method has been carried out skilfully.

It will be noted that the edges of the two strips of fabric do not meet each other in Figs. 5 and 6. On the other hand Fig. 7 shows that said edges may be lapped a little at both sides of the tire, and Fig. 8 shows that they may be lapped at one side as at 8 15 and may be spaced at the other side as at 9. By this word "spaced," I mean that the edges may be left separated from each other, so that between them there is nothing but the two or more convolutions or layers of 20 rubber, vulcanized to each other direct. Such a space I do by preference leave at each side of the tube, because where the fabric is inserted the tube loses its expansibility without losing its flexibility, and ordinarily 25 it should expand at some point so that when inflated it will fill the casing. The expansion point or points I prefer to make in the shape of a band along one side or bands 30 along both sides of the tube, rather than 35 along its tread or its rim side, because the tread side is subject to wear within the casing as well as the rim side, and both need the protection of the strip of fabric, and therefore the sides of the tube are the proper 40 places to omit said fabric.

In Fig. 9 the expansion bands are reinforced by rather narrow strips 10 of rubber which overlap the edges of the fabric strips and extend across the bands, and these rubber strips will of course be vulcanized to the rubber convolutions in making the tube.

In Fig. 10 I have illustrated the possibility of amplifying this method by the addition of other strips of fabric, as when the 110 tube must be made very strong, for use for instance on motor trucks. Herein I have illustrated an additional strip at 11 on the tread side, making two strips herein all, although of course there could be a greater 115 number; but in this view I have not amplified the number of strips on the rim side, because one thickness of fabric will ordinarily be sufficient at that point, although I do not wish to be limited to the same. It is 120 essential, however, that the rim-side fabric-strip shall be stretched to such an extent that it may be said to be expanded before being applied, so that the principal feature 125 of my invention will result as above explained. A tube constructed in this manner may be employed as an ordinary hose-pipe tire which has no outer casing. I have also made use of Fig. 10 to show that metallic or 130 leather or other strips or plates of armor

may be inserted as at 12 (preferably between the several fabric layers on the tread side) to give greater strength to a tube of this kind, whether it be used with a casing 5 or without, but of course this feature of armoring the tube might be employed in other ways than as herein shown.

Fig. 11 is a diagrammatic section through the tube at right angles to its axis and on a smaller scale. Herein is shown how I cause the meeting ends of the various strips to break joint with each other around the tube, the obvious reason being because where these ends meet the tube is weaker and I 15 would there ~~are~~ have the weakened points lie opposite ~~unbroke~~ portions of other thicknesses ~~or~~ layers of fabric. It will hardly be necessary to give illustrations of the manner in which a tube thus made is 20 built up, but it will be clear to those familiar with the business that the several layers of fabric on the tread side will be properly applied before the sheet 5 is rolled as shown in Fig. 5, or some of the layers could be in- 25 side the second convolution and others out- side it and the convolutions themselves am- plified so that a thicker tube would result; and in bringing the ends of the tube to- 30 gether to complete the finished article, the longer end of one layer on the tread side will be inserted into the proper space for it between the convolutions of the rubber sheet 5 at the other end, so that the break joint feature above referred to will be car- 35 ried out. I have purposely omitted giving proportions of parts as they are not essen- tial to the successful operation of my method.

Refinements and additions may be made 40 as will be clearly understood. For instance, the inflating nipple and valve will be applied in the ordinary manner and at a proper point, but I consider it unnecessary to illustrate this feature or the tire casing. 45 Wear strips 15 and 16 may be applied along the outer and inner sides of the finished pneumatic tube as shown in Fig. 7 so as to prevent the same from being worn by the inside of the tread of the casing or chafed 50 or pinched along the seam at the rim side of the casing; these strips may be applied by cementing them onto the finished tube, or they might be applied before vulcanizing the component parts together and in that 55 case the strip along the rim side will by preference be cut bias and expanded in the manner above set forth.

As above suggested, I prefer that expansion bands be left along one or both sides 60 of the tube, where the material of the same is wholly rubber, although this is not absolutely necessary and may be omitted in some instances. Its purpose is to permit the tube to expand along these bands rather than 65 on the tread or the rim side. Also I prefer

that the entire inner convolution shall be of rubber or rubber composition, so that it will be air tight which some fabric is not. The fabric may be treated to make it impervious to moisture, and it may be treated to resist 70 the heat sometimes generated under heavy loads or high speed.

What is claimed as new is:

1. A pneumatic tire tube comprising a body of rubber, a strip of fabric carried by 75 the tread portion of said rubber body, and a strip of expanded bias fabric carried by the rim portion of said body.

2. A pneumatic tire tube comprising a body of rubber, a fabric strip carried by the 80 tread portion of said body, a second strip of bias fabric carried by the rim portion of said body and expanded circumferentially, the edges of said strips being spaced at one side of the tube leaving an expansion band 85 of rubber.

3. A tube for pneumatic tires comprising an elastic body having a strip of fabric carried by the tread portion thereof, a second strip of longitudinally expanded bias fabric 90 carried by the rim portion of the body, the edges of said fabric strips on one side of the tube being spaced to leave an expansion band at said side of the tube and a strip of rubber overlapping said spaced edges and 95 extending across the expansion band.

4. A pneumatic tire tube comprising a rubber body, and a strip of expanded fabric embedded in said body along its rim side.

5. A pneumatic tire tube comprising a 100 rubber body, and a strip of expanded bias fabric embedded in said body along its rim side.

6. The herein described inner tube for pneumatic tires which consists of a tubular 105 rubber body, along the tread side thereof a fabric strip of normal mesh, and along the rim side of said body a bias fabric strip expanded while the tube is deflated and of normal mesh when it is inflated in a casing 110 of proper size.

7. A rubber tire tube having embedded along one side thereof a fabric strip ex- panded longitudinally and to a greater de- gree along the center of the strip than along 115 its edges.

8. The herein described inner tube for pneumatic tires comprising a piece of straight elastic rubber tubing having its ends united, a strip of fabric embedded in 120 its tread side and substantially correspond- ing in length with the internal circumfer- ence of the shoe or casing which receives the tube, a second strip of fabric embedded in a longitudinally stretched condition in 125 the rim side of the tube, the threads of the second fabric strip running diagonally, and the edges of the two strips being spaced apart at the sides of the tube leaving ex- pansion bands wholly of rubber, and strips 130

of elastic rubber overlapping said spaced edges and extending across the expansion bands.

9. A pneumatic tire tube comprising a rubber body, and a strip of bias fabric expanded longitudinally and embedded in said body along one side thereof.

In testimony whereof I have hereunto set my hand in presence of two subscribing witnesses.

CLARK FRANCIS FISK.
